UNITED STATES PATENT OFFICE.

JAMES McALEAR AND ERNEST W. RIESBECK, OF CHICAGO, ILLINOIS, ASSIGNEES TO THE McALEAR MFG. CO., OF CHICAGO, ILLINOIS, A CORPORATION OF ILLINOIS.

CONTROLLING DEVICE FOR HEATERS.

Application filed June 18, 1917. Serial No. 175,393.

To all whom it may concern:

Be it known that we, JAMES McALEAR and ERNEST W. RIESBECK, citizens of the United States, residing at Chicago, in the county of Cook and State of Illinois, have invented certain new and useful Improvements in Controlling Devices for Heaters, of which the following is a specification.

This invention relates to controlling and regulating devices for heaters, and has for its object to provide a new and improved device of this description adapted to be connected to the heater and particularly adapted to be used to automatically control the heaters such as the radiators of a steam heating system, so that each heater may be independently controlled by regulating the admission of the steam thereto, and hence the heating of the apartment containing such heater.

The invention is illustrated in the accompanying drawings wherein—

Fig. 1 is a view showing a heater with one form of the controlling device in position.

Fig. 2 is an enlarged vertical section through the controlling device.

Fig. 3 is an end view looking in the direction of the arrows 3—3 of Fig. 2.

Fig. 4 is a view showing a device similar to that of Fig. 2 with parts broken away, connected up both with the admission and return of the heater.

Fig. 5 is a view in part section showing a modified construction.

Fig. 5^a is a sectional view taken on line 5—5^a of Fig. 5.

Fig. 6 is a view in part section showing a further modified construction.

Fig. 7 shows a further modification.

Like numerals refer to like parts throughout the several figures.

Referring now to Fig. 1, we have shown a heater 1 provided with an admission pipe 2 and return pipe 3. Located in the admission pipe is a controlling and regulating device 3^a. One form of this device is illustrated in detail in Fig. 2. As shown in this figure, a casing 4 is connected in the admission pipe 2 and contains a valve 5 adapted to seat on a seat 5^a. This valve is provided with a stem 6 which projects through the section 4^a of the casing. This valve stem passes through an adjustable part 8 having a sliding connection therewith and a spring 7 surrounds the valve stem and engages the

part 8 and a part 9 on the end of the stem. Said spring tends to hold the valve 5 away from its seat. The valve stem projects into the controller casing 10 containing the controlling element for the valve. This casing is provided with a heating chamber 11 which is heated in any desired manner. As herein shown, the valve stem 6 is provided with an opening 12 having a discharge end 13 and through which fluid passes into the heating chamber 11. Associated with the heating chamber is a power chamber 14 which contains some material which develops power when heated, as for example, an expanding fluid such as a liquid which when heated is converted into a vapor or a gas. The power chamber 14 has a communication leading to the controlling chamber 15. In the construction shown, this communication consists of the passageway 16, the chamber 17 and the passageway 18. This connection is controlled in some desired manner and as herein shown we provide a controlling device responsive to the variations in the temperature of the apartment, said device, as shown, being a thermostatic device consisting of a valve 19 which engages a seat 20 at the end of the passageway 16. This valve is actuated by a thermostat 21 which is mounted so as to move the valve as the temperature varies.

In the construction shown this thermostat has one end connected with the valve stem and means is provided for adjusting it so that it acts under different ranges of temperature. This adjustment is secured by means of a screw 22 which engages the thermostat (see Fig. 2) and which is controlled by the movable indicating device 23 having a pointer 24 which works along a graduated scale 25, said scale indicating the temperatures at which the device operates.

It will be seen that by moving the part 23 the temperature at which the valve 19 is operated can be varied. The thermostat 21 is arranged so that the air in the apartment passes by it, said air passing upward through the openings 26 and 27. In the particular construction shown the valve stem 19^a of the valve 19 is connected with two diaphragms 28 and 29 by the yoke 30 which passes around the part 31 containing the valve 19, the two diaphragms being, as it were, in the same chamber so that when the fluid from the power chamber passes into

this chamber, it will act upon both diaphragms and thus produce a balanced condition so that it has no effect on either opening or closing the valve. One side of each 5 diaphragm is exposed to the atmosphere. This connection is made to one side of the diaphragm 29 by the openings 29^a. When the temperature in the apartment rises above a predetermined point, the thermostat is 10 moved so as to move the valve 19 away from its seat and permit the power fluid from the power chamber to pass into the controlling chamber 15 where it acts to move the valve stem and force the valve 5 down upon its 15 seat, thereby cutting off the supply of the heating fluid to the heater.

In Fig. 2 the controlling chamber 15 contains the flexible diaphragm or bellows and expansion disk 32 which connects with the 20 valve stem 6. When the power fluid passes into the chamber 15 the pressure thereof compresses this flexible bellows so as to move the valve stem to force the valve 5 against its seat. Connected with the valve stem 25 and surrounding the spring is a sleeve 32^a which slides in the threaded sleeve 33 and which prevents the steam from the heating chamber 11 from passing into the controlling chamber 15. We prefer to provide one 30 or more grooves 34 between the two sleeves, the water produced by the condensed steam entering these grooves and forming a packing. This device may be arranged so that it can be applied to the heaters as now used 35 by simply attaching the casing 10 to the part 4^a of the valve casing now used on radiators.

In the construction of Fig. 2 when the 40 expansible liquid is heated and converted into a vapor or a gas it passes up into chamber 15 when the thermostat opens the valve 19. When the thermostat closes the valve, the gas in chamber 15 gradually condenses 45 into a liquid and runs down into the space below the valve stem 19^a. The condensation of this gas lowers the pressure in chamber 15 so that when the valve 19 is again opened the gas will rush into chamber 15 and again 50 act to close the main valve 5. When the liquid in the chamber below valve stem 19^a rises to a level above the opening controlled by the valve it will flow back into the chamber 14 when the valve is opened.

In Fig. 4 we have shown a device 55 connected up both with the admission and return of the heater. In this figure the controlling apparatus is similar to that shown in Fig. 2 with the exception that the inlet opening 35 is controlled by two valves, the 60 valve 5 and the valve 36. The valve 36 is contained in the additional casing 37 which is connected in the return pipe 38 of the heater. The valve 36 is controlled by a 65 suitable thermostatic device so that when the radiator is filled with heating fluid and

it passes out through the return pipe, it strikes this thermostatic device and causes the valve 36 to be moved to close the opening 35, and thus shut off the admission of the heating fluid to the heater. 70

As shown in Fig. 4 this thermostatic device consists of an expansion disc 39 which contains expansible fluid, either liquid or gas, the valve 36 being connected therewith so that when the heating fluid passes 75 through the casing, it expands and moves the valve 36 to its closed position. There is some suitable retracting device, as for example, the spring 40. The stem 41 of the valve 36 is preferably packed in some suitable manner as by means of the water packing rings 42. In this construction we have also provided a passageway 43 which connects the heating chamber 11 with the admission pipe 2 so that steam can pass into 85 the heating chamber when the valve 36 is closed.

It will be seen that with this construction during the period the valve 5 is opened, the valve 36 will be intermittently closed and 90 opened, for as soon as the heating fluid passes into the heater and out the pipe 38 and strikes the expansion disc 39, the expansion thereof moves the valve 36 to its closed position. Further admission of heating fluid is then stopped and heating fluid, such for example as steam, remaining in the heater, will be condensed, thus producing a vacuum, or partial vacuum, in the 95 heater. The expansion disc 39 will then be cooled by the water of condensation or the interruption of the flow of steam, the valve 36 opened and more heating fluid admitted, and this intermittent action will continue 100 until the temperature of the room rises to the predetermined temperature which causes the controlling device for the valve 5 to act, whereupon the said valve is closed, shutting off the heating fluid from the heater. By 105 means of this construction the heater is operated either at or below atmospheric pressure both with or without a vacuum producing device attached to the return pipe 38, thus itself regulating the temperature 110 and giving an efficient action and a moderate 115 heat.

In Fig. 5 we have shown a modified construction where the valve stem 6 is connected with the expansion disc 32 as shown in Fig. 2, but the thermostat control for the power fluid is arranged in a different manner. In this construction the thermostat 55 which contains an expansible fluid is mounted in a tube 56 provided with openings 57 for the passage of air into and out of the tube so as to permit the air to come into contact with the thermostat. The thermostat is mounted upon the adjustable support 58. The thermostat is connected with a rod 59 attached to a valve 60 which controls the 120 125 130

admission of the power fluid from the power chamber 14 to the controlling chamber 15, the fluid passing through passageways 61 and 62. The rod 59 is also connected with 5 a diaphragm 63 and a spring 64 tends to move the valve 60 in one direction while the spring 65 tends to move it in an opposite direction. It will thus be seen that when the temperature of the apartment reaches a 10 predetermined point, the thermostat 55 moves the valve 60 to permit the power fluid to pass through the passageways 61 and 62 to the controlling chamber 15 where it acts upon the discs 32 so as to cause the 15 valve 2 to be closed. In this construction the device is adjusted by means of the threaded connection between the casing 10 and the section 4^a, the raising of the casing 10 causing the valve to close more slowly 20 and the lowering of it causing it to close more quickly. The casing is held in any of its adjusted positions by the adjusting nut 66.

In Figure 6 we have shown a modified 25 construction where the pressure of the heating fluid itself is used to close the valve. In this construction the valve stem 6 is provided with a passageway 46 which extends to the wall 47 there being an opening 30 48 which communicates with the passageway 49 leading to the disc 52. This passageway is controlled by a valve 50 connected to a valve stem 51 adapted to be actuated by a thermostat 52. As shown, the valve stem 35 51 is in proximity to a diaphragm 53 which is engaged by one side of the thermostat, the other side engaging the adjustable stop 54. The thermostat is provided with an expansible fluid and is mounted so as to be 40 open to the atmosphere in order that the air in the apartment to be heated may come into contact with it. The valve is normally held closed by a spring 55^a. When the temperature of the apartment reaches a predetermined point the expansible fluid is expanded so as to move the thermostat to open 45 the valve 50. This permits the heating fluid to pass through the passageway 49 to the casing 32^c and into the expansion disc 32^a. 50 The heating fluid then exerts a pressure on the disc to expand it and moves the valve stem so as to move the valve 5 to its closed position. When the temperature of the apartment falls, the thermostat moves so 55 as to permit the spring 55^a to close the valve 50 and shut off the heating fluid from the disc 32^a. When the pressure on this disc is lowered, the spring 56^a moves the stem 6 so as to open the valve 5. Any of the heating 60 fluid, when the heating fluid is steam, for example, which is condensed, may pass out through the passageway 57^a in the valve stem and the passageway 58^a in the removable section 59^b. The valve 59^a automatically 65 opens to let the water of condensation pass

out but closes to prevent the steam from passing up through the passageway 58^a. A packing gland 60^a for the valve stem may be provided and there may also be provided the packing grooves 61^a and 62^a arranged 70 to receive water of condensation which acts as a packing.

In Fig. 7 we have shown a further modification. This construction is similar to Fig. 6 except that the passageway 49 communicates with the casing 63^a containing the disc 32^b so that the pressure of the heating fluid is applied to the exterior of the disc instead of to the interior thereof.

We claim:

1. A regulating device for heaters comprising a casing, a valve for controlling the admission of the heating fluid to the heater, a controlling element connected with said valve for moving it to its closed position, a controlling chamber in said casing containing said controlling element, a power chamber containing expansible fluid, means for heating said expansible fluid by means of a portion of said heating fluid, a connection 90 between said power chamber and said controlling chamber, a valve for controlling said connection and a thermostat for operating said valve, said thermostat responsive to variations in temperature in the apartment to be heated.

2. A regulating device for heaters comprising a valve casing, a valve therein controlling the admission of the heating fluid to the heater, a stem connected with said valve, a heating chamber associated with said valve stem, a power chamber in proximity to said heating chamber so as to be heated thereby, said power chamber containing a fluid which expands when heated, a controlling chamber, a connection between said power chamber and said controlling chamber, means for opening said connection responsive to variations in temperature in the apartment to be heated so as to admit the power fluid to the controlling chamber and means for applying the pressure of said power fluid in said controlling chamber to said valve to move it to its closed position.

3. A regulating device for heaters comprising a valve for controlling the admission of the heating fluid to the heater, means for actuating said valve comprising a power chamber containing power fluid, a controlling chamber separate from said power chamber, a normally closed connection between the power chamber and the controlling chamber, a thermostatic device for opening and closing this connection in response to variations in temperature in the apartment to be heated, means for utilizing the heating fluid to heat said power fluid to cause it to expand and pass into said controlling chamber and means in said controlling chamber for applying the pressure of said power

fluid admitted to said chamber, to move said valve towards its closed position.

4. A regulating device for heater comprising a valve for controlling the admission 5 of the heating fluid to the heater, a stem for said valve, a controlling chamber into which said stem projects, a disc in said controlling chamber connected with said stem, a power chamber containing an expansible 10 fluid, means for heating said power chamber, a normally closed connection between said power chamber and said controlling chamber, a valve controlling said connection, a thermostat connected with said valve and 15 responsive to variations in temperature of the apartment to be heated and adapted when the temperature reaches a predetermined point, to open said connection and admit the power fluid to the said controlling 20 chamber so that it acts upon said disc to move said first named valve towards its closed position and means for moving said valve to its open position when the pressure of said disc has fallen to a predetermined 25 point.

5. A regulating device for heaters comprising an admission pipe for admitting the heating fluid to the heater, a valve for controlling said admission pipe, a stem for 30 said valve, a controlling chamber into which said stem projects, a disc in said controlling chamber connected with said stem, a power chamber containing an expansible fluid, a heating chamber in proximity to said power 35 chamber, means for admitting the heating fluid into said heating chamber, a normally closed connection between said power chamber and said controlling chamber, a valve controlling said connection, a thermostat 40 for actuating said valve, said thermostat responsive to variations in temperature of the apartment to be heated, and adapted when the temperature reaches a predetermined point to open said connection and admit the 45 power fluid to the said controlling chamber so as to act upon said disc to move said first named valve towards its closed position and a spring connected with said valve stem and opposing the pressure of said power 50 fluid.

6. A regulating device for heaters comprising a valve for controlling the admission 55 of the heating fluid to the heater, a controlling element connected with said valve for moving it to its closed position, a controlling chamber containing said controlling element, a power chamber containing an expansible fluid, means for heating

said expansible fluid by means of a portion of said heating fluid, a connection between said power chamber and said controlling chamber, a valve for controlling said connection and a thermostat for operating said valve, said thermostat responsive to variations in temperature in the apartment to be heated, all of said elements being connected together so as to form a compact structure and means for connecting said structure with the admission pipe of said 70 heater so as to form a single compact structure whereby the controlling mechanism for each heater is independent of the controlling mechanism for any of the other heaters. 75

7. A regulating device for heaters comprising a casing adapted to be connected with the admission pipe of the heater, a valve mounted in said casing for controlling the admission of the heating fluid to the heater, means for actuating said valve comprising a power chamber in said casing and containing a power fluid, a controlling chamber in said casing separate from said power chamber, a normally closed connection between the power chamber and the controlling chamber, a thermostatic device supported by said casing for opening and closing said connection in response to variations in temperature in the apartment to 90 be heated and means in said controlling chamber for applying the pressure of said power fluid admitted to said chamber, to move said valve towards its closed position. 85

8. A self contained regulating device for 95 heaters comprising a valve casing, a valve therein adapted to control the admission of the heating fluid to said heater, a valve stem connected with said valve, a pressure receiving device connected with said valve stem 100 and adapted when the pressure of a power fluid is applied thereto to move the valve to close it, said valve casing having a passageway therein for connecting a source of power fluid with said pressure receiving device, a valve mounted on said casing for controlling said passageway, and a thermostat mounted upon said casing for controlling said valve, said thermostat responsive to variations in temperature of the 110 apartment to be heated. 105

Signed at Chicago, county of Cook and State of Illinois, this 29th day of May, 1917.

JAMES McALEAR.
ERNEST W. RIESBECK.
